(57) **CLAIM**

The ornamental design for a faucet handle as shown and described.

DESCRIPTION

FIG. 1 is a front perspective view of a faucet handle, showing my new design;

FIG. 2 is a front elevation view thereof;

FIG. 3 is a rear elevation view thereof;

FIG. 4 is a side plan view thereof;

FIG. 5 is a side plan thereof;

FIG. 6 is a top plan view thereof;

FIG. 7 is a bottom plan view thereof; and,

FIG. 8 is a second perspective view of a faucet handle. The broken lines are included for the purpose of illustrating portions of the faucet handle and form no part of the claimed design.

The stippling technique used in FIGS. 1-5 and 7-8 is to a show contrast of surface texture of the faucet handle.
